SPENCER OTIS, OF CHICAGO, ILLINOIS.

BOILER-WASHING SYSTEM.

Application filed November 19, 1920. Serial No. 425,059.

To all whom it may concern:

Be it known that I, SPENCER OTIS, a citizen of the United States, residing at Chicago, in the county of Cook and State of Illinois, have invented certain new and useful Improvements in Boiler-Washing Systems, of which the following is a specification.

This invention relates to systems for washing out and refilling boilers, for instance, locomotive boilers, and is designed primarily for the washout portion of such a system, although some of its features are applicable as well to the refilling part thereof.

10 In my application Serial No. 321,274, I have described and claimed a system of hot water distribution, in which water is circulated from a storage receptacle through a system of pipes which constantly direct it to 15 and past a place where it is accessible for use (in the illustrated instance, use by consumption of the water in heated state for refilling of boiler), and the circulation being continued, when not being drawn upon, so as 20 to keep up the flow in the pipe and back to the storage receptacle, and insure presence of hot water at the service outlets at all times besides protecting the line against injury 25 from freezing in extreme weather; the water returned to the receptacle being re-conditioned while yet outside of the receptacle, or 30 just before its discharge thereinto; and self-controlled means for determining the degree of reconditioning being provided and made 35 dependent upon the temperature of the returned water or heat loss incident to its circulation, so that it entered the receptacle at suitable temperature for re-admission to the 40 circulating line.

40 One object of the present invention is to organize such a self conditioning water circulating system as a temperature reducing means so that it may be employed with advantage in combination with the washout portion of a boiler washing system as a 45 means for tempering the washout water and economizing in the quantity of fresh water required to be mixed with blown off water stored in the washout tank to render it safe 50 for use through the boiler washing hose. One feature of the present invention consists, accordingly, in combining such a circulating system and conditioning apparatus with the washout tank of a boiler washing 55 system, and collateral features incident to the preferred embodiment thereof consists in

having the thermostatic control of the conditioning apparatus subject to temperatures of the storage tank after accretion of the returning water, so that the tank temperatures 60 rather than returning water temperatures will be regulated; also in having not only means for making up excessive temperature losses on the circulating line, but for determining whether the returning water goes 65 back to the storage tank or is delivered to waste, and having this determination depend upon the quantity of water already in the storage tank, so that if the storage tank has been charged to its full capacity by additional blown off water, the returning water 70 will automatically pass to sewer.

Another object of the present invention is to adapt the self conditioning circulatory system to serve not only as a means for cutting down the temperature of washout water, but as a means for heating the atmosphere of the roundhouse or other place of operation in which the system is installed; in other words, increasing the efficiency of 80 heat dissipation and at the same time serving the useful purpose with the heat so radiated. Another feature of the invention accordingly consists in introducing into the circulating line, either directly or in shunt 85 through the pipes thereof, suitable radiators forming parts of the circuit of circulation; collateral features to this part of the invention consisting in combining with the circulating system boosters of temperature, and, 90 if desired, also of the water flow, which will take care of excessive drops in temperature under extreme conditions and give full capacity to the system as a heating apparatus as well as insuring circulation through the 95 shunt lines; the action of a booster being automatically controlled by a thermostat which is subject to the temperature effect at or near the point in the pipe circuit which is to be influenced.

100 The invention will be understood upon reference to the accompanying drawings in which one embodiment is shown by way of illustration, and in which—

Figure 1 is a schematic view showing the 105 layout of a boiler washing system with which the several features of the present invention are combined.

Fig. 1^A is a detail sectional view of the diaphragm valves entering into the organization of Fig. 1.

Figure 2 is a detail sectional view of a

triple by-pass valve which enters into the organization of Figure 1, and parts of which are responsive, respectively, to temperature and hydrostatic conditions in the washout tank.

Figure 3 is a detail view partially in section of a temperature and circulation booster employed in Figure 1; and

Figure 4 is a sectional detail view of a modified construction of the booster shown in Figure 3.

1 represents the washout tank of a boiler washing system which receives its main water supply through pipe A from the separator B, which receives the contents blown off from a boiler through the blowoff pipe C, steam from the separator passing through crossover pipe D to the condenser E, whence it passes to the filling tank F.

20 It is customary in systems of this kind to provide pumps such as 2, 2^a, for keeping up pressure on the washout line 3 and the filling line 3^a with their drops or outlets 3^x and 3^ax, water flowing through the washout line being usually at a high temperature in consequence of being received from the blown off products of the locomotive, and being tempered by the thermostatic action of cold water to bring it down to a temperature 25 which will not injuriously affect the operatives in handling the washout hose. Such a system of operation is wasteful as to cold water consumed.

The present invention provides special 35 means for reducing the temperature of water in the washout tank 1 by radiating the heat therefrom along the line, or shunt piping connected with the line, so as to either reduce or render unnecessary the addition of 40 tempering water to the supply maintained in the washout line 3; and to this end, said washout line is provided with the usual return pipe 4, and in addition to having this 45 return pipe delivered directly into the washout tank 1, for instance through the medium of the branch pipe 4^a, it is also connected through a pipe 4^b with a conditioning apparatus 5, adapted to raise the temperature of the returning water by the admission of 50 steam through the branch 6^a whenever the temperature of the tank, into which the returned water is delivered, falls below a predetermined temperature, for instance, 140° F.; and said return pipe is further 55 provided with a by-pass valve 7 moved by steam piston 7^a which receives steam pressure from the diaphragm valve 7^b in turn controlled by the thermostat 9, so that the returning water will pass directly to the 60 tank through the pipe 4^a when the temperature in tank 1 is up to 140°, or pass into said tank indirectly through pipe 4^b and steam heater 5 whenever the temperature falls undesirably, say, below 120°.

65 Preferably valve 7 is made in the form of

a triple valve with two valve heads as shown in Figure 2, one of its valve heads 7^c acting to seat downward and divert water from pipe 4^b, or to seat upward and cut off access to pipe 4^b while permitting the water of pipe 4 to escape downwardly; while the other valve head 7^d may move into a position which permits the return water to flow from pipe 4 to pipe 4^a and directly into tank 1, or into a position which will cut off communication with the tank 1 and permit the return water to flow through waste pipe 4^c into the overflow pipe 1^a of the tank 1, according to the height of water in the tank 1, which will exert its control hydrostatically upon the valve head 7^d through means of the diaphragm 7^e communicating through pipe 7^f with the piston 7^g which is connected to said valve head.

It is customary to control the pump 2 by the load on the line 3 so that when no hot water is being drawn from the line for washing out purposes there is merely a circulation kept up, through return pipe 4, sufficient to keep up the temperature of the water at the outlets, and to this end diaphragm valve 8 is suitably connected with the pressure outlet 8^a in the pipe 3 beyond the pump 2.

In order to increase radiation on the circulating line various radiating devices are employed, preferably in such places as will enable them to serve useful purposes in heating the atmosphere in the roundhouse or other work places, as suggested by the common type of floor radiator 9, the pit radiator 10, and the wall radiators 11 and 12. These radiators are on the circulating line that is connected in shunt between the washout line 3 and the return pipe 4, as, for instance, through the medium of branch pipe 13, connecting pipes 14, 15, 16, and terminal pipe 17. With this means, excessive heat in the tank 1 may be effectively dissipated, and at the same time saved from waste in seasons when artificial heat in work rooms is desirable, by causing the heat to warm up the atmosphere of such rooms.

In order to make the heating system effective in extreme temperatures, provision may be made for replacing excessive loss of heat by radiation in some of the radiators, for instance, the radiators 9, 10, and 11, by providing a heat booster 18 in advance of one, or more of the radiators, for instance, radiator 12, and this heat booster may be controlled automatically by the temperature of water of circulation as it reaches the point of the booster, as suggested in Figure 3, by putting in a thermostat 18^a controlling diaphragm 18^b with live steam pipe branch 19. In order that the accretion of steam may be under conditions which also speed the circulation of the water, it may be delivered into the connecting pipe 16 by means of a

- nozzle 19^a presented in the direction of flow. By the means shown in Figure 3, the temperature of the water as well as the flow of the water in the shunt connected heating line will be insured. This result will also be favored by the proper proportioning of the return pipe 4 in advance of and subsequent to the tapping in of the terminal pipe 17.
- 10 As suggested in Figure 4, the heat booster may be increased in its effect by having, in addition to the nozzle 19^a delivering steam under control of thermostat 18^a, an additional booster 20, thermostat 20^a, and steam nozzle 21, the thermostat 20 being in position to be responsive to the temperature of water of circulation after the accretion of steam and heat delivered by the nozzle 19. The heat boosters 18 and 20 will obviously have their effect 15 upon the temperature of water returning through pipe 4, and where they are in operation it may not be necessary to return the water through the conditioning heater 5. Moreover, the necessity for action of the boosters 18 and 20 should exist only when the temperature is falling below that at which it should reenter the tank 1, and thermostats 18^a and 20^a may readily be adjusted so that they will put the nozzles 19 20 and 21 into play only at such times.
- Obviously, instead of tapping the terminal pipe 17 into the return pipe 4, it could be tapped directly into the washout line 3.
- I claim:
- 35 1. In a boiler washing system, a washout tank, a washout line, a return pipe having two channels through which it returns water to the washout tank, a temperature conditioning device introduced into one of 40 said channels of communication, and a temperature controlled valve adapted to connect the return pipe with either of said channels of communication.
2. In a boiler washing system, a washout 45 tank, a blowoff connection adapted to supply water to said washout tank, a washout line, a return pipe adapted to deliver returned water of circulation to said tank, a waste pipe, a valve adapted to connect the 50 return pipe alternately with the washout tank and the waste pipe, and means actuated by the height of water in the washout tank for controlling said valve.
3. In a boiler washing system, a washout
- 55 tank, a washout line, a return pipe for returning water of circulation delivered through the washout line, a temperature conditioning device communicating with said tank, a direct delivery pipe communicating with said tank, a waste pipe, and a triple valve having a hydrostatic column control through which it directs water to the waste pipe or to the tank according to the volume of water in the tank and having a temperature control through which it passes water from the return pipe to the tank either through the direct communication or through the temperature conditioning device according to the temperature of water in the tank.
- 60 4. In a boiler washing system, a washout tank, a system of circulation for washout water supplied from said tank, and radiators introduced into said system of circulation through which washout water flows.
- 65 5. In a boiler washing system, a washout tank, a system of circulation for washout water supplied from said tank, including a washout line, a supply outlet for said washout line, and a return line, and a system of water circulation connected in shunt with 70 said first-named system of circulation and including radiators in its circuit.
- 75 6. In a boiler washing system, a washout tank, a system of circulation for washout water supplied from said tank, including a washout line, a supply outlet for said washout line, and a return line, and a system of water circulation connected in shunt with 80 said first-named system of circulation and including radiators in its circuit; said shunt 85 system of circulation receiving water from the main washout line and discharging its water of circulation into the return pipe of the system of circulation first named.
- 90 7. In a boiler washing system, a water circulating system, means for delivering water therefrom to a boiler at will, and radiators supplied from said circulating system.
- 95 8. In a boiler washing system, a water circulating system, means for delivering water therefrom to a boiler at will, radiators supplied from said circulating system, and means automatically maintaining temperature of water in the circulating system.
- 100 Signed at Chicago, Illinois, this 15th day of November, 1920. 105
- SPENCER OTIS.
